UNITED STATES PATENT OFFICE.

CHARLES W. FISCHER AND RUDOLF SCHAMBER, OF GREGORY, SOUTH DAKOTA.

SAFETY-CARRIER.

1,224,086.

Specification of Letters Patent. Patented Apr. 24, 1917.

Application filed January 8, 1916. Serial No. 71,016.

To all whom it may concern:

Be it known that we, CHARLES W. FISCHER and RUDOLF SCHAMBER, citizens of the United States, residing at Gregory, in the 5 county of Gregory and State of South Dakota, have invented certain new and useful Improvements in Safety-Carriers, of which the following is a specification.

The article which constitutes the subject 10 matter of this invention is designed primarily as a mail carrying device but owing to its structural characteristics several other adaptations are comprehended within the purview of its utility.

15 The main object in view is to provide inclosing means of a strong and substantially rigid character adapted to receive communications, cards, tags or similar articles subject to transmission through the mails or 20 other shipment, and embodying locking means so arranged as to preclude unauthorized removal of or otherwise tampering with the contents without detection.

Another object is to provide against 25 displacement of the locking means aforesaid through the instrumentality of a seal, such seal in one of the adaptations of the invention constituting the postage requisite for transmission of the article through the 30 mails.

A still further object in mind is to provide a removable section for the inclosing means such that upon displacement of said section, the device will form a suitable picture frame.

These and such other objects as may hereinafter appear are attained by the novel construction, combination and arrangement of parts to be hereinafter specifically described 40 and claimed. Reference will now be had to the accompanying drawings forming a part of this specification, wherein:—

Figure 1 is a perspective view of an embodiment of the invention ready for transmission through the mails.

Fig. 2 is a longitudinal sectional view taken on the line 2—2 of Fig. 1.

Fig. 3 is a vertical sectional view on the line 3—3 of Fig. 4.

Fig. 4 is a front elevation of the device.

Fig. 5 is a perspective view of the article subsequent to the detachment of the removable section or panel.

Fig. 6 is a plan view of the invention in 55 open position.

Fig. 7 is a perspective view of the locking member used in connection with the device.

Throughout the following description, and on the several figures of the drawings, similar parts are referred to by like reference 60 characters.

Specifically referring to the drawings and describing the invention, it will be understood that the article forming the subject-matter thereof is susceptible of being made 65 or formed from different materials such as tin, but preferably aluminum or celluloid, or like substances. The main point, however, is the utilization of a material which will be sufficiently strong and durable to permit 70 of the rough usage incident to transmission through mails and which will enable the article to be used a number of times.

The carrying device might be said to comprise a form of receptacle consisting of co- 75 operative sections, namely a front section 1 and a rear section 2, preferably integrally connected at one end 3. That is to say, the

material from which the article is made is folded back upon itself and the end 3 therefore 80 constitutes a hinge-like connection enabling the receptacle or container to be opened and closed. The front section 1 is provided with a plurality of sight openings as designated 4 in order to disclose indicia, 85

such as names and addresses which are borne by a communication or other content inserted between the two sections and which it is designed to transmit or protect. In the cutting out of the material to form cer- 90

tain of these sight openings 4, a sufficient portion thereof is utilized to constitute one or more eyes 5, such eyes being formed by rolling the material back on the inner side 95 of the front section as most clearly shown in Figs. 3 and 6. This section, further-

more, is provided along its lateral edges with inwardly bent flanges at 6 into which the contents of the container are adapted to be inserted, said flanges holding the communica- 100 tion or card, as the case may be, against the front section so that the indicia thereon will be properly positioned with respect to the sight openings 4.

The rear section 2 of the container is ob- 105 viously similar in shape to the front section being provided with lateral flanges 7. When the container is closed the front section 1 is folded into position between the flanges 7, said flanges being of a resilient character and 110

yielding as the front section is pressed into proper contiguous relation to the rear section. It will be apparent that these flanges prevent the contents from accidentally slipping out of the container during use of the same. The rear section, in addition, has an end flange 8 which performs a like function and is similar in formation to the flanges 7 so that when the article is in closed condition a smooth edge is presented and therefore likelihood of injury to other mail matter is precluded.

One of the novel features of construction of the rear section 2 is the formation thereof with a removable panel or section 9. It will be observed by reference to Figs. 4 and 6 that the material of the rear section is cut out as indicated generally at 10, a sufficient amount of the material being left, however, to connect the central panel 9 to the side portions of the section, these connecting portions constituting the tongues 11. This construction enables the container to be utilized as a frame, for instance, where it is desired to preserve a picture postcard that might have been received in the container. In order that this may be done the central section 9 is detached or removed by severing the tongues 11 from the rear section, allowing the panel to drop out. The article then takes the form of the framelike container shown in Fig. 5 having an enlarged central opening to disclose the picture on the article held in said container.

In cutting out the material of the rear section 2 a sufficient amount is retained at one end to provide for formation of one or more locking eyes 12 corresponding to the eyes 5 on the front section. The eyes 12, however, are arranged in different planes from the eyes 5 so that when the sections are folded together the eyes 5 and 12 will coöperate or take an alined position as shown in Figs. 3 and 4. When in the alined position, a locking member 13 is inserted into said eyes thereby holding the two sections in closed position. To enable the insertion of the locking pin or member 13, the material of the front section is provided with an opening 14 through which the member 13 is introduced transversely of the container. The member 13 is formed with a bent extremity 13' which facilitates the manipulation of the locking member when inserting or retracting it from its operative position. One of the main features of this invention lies in the effective sealing of the container to prevent disturbance of the contents without detection and this is accomplished by placing a seal over the opening 14. The locking member is thus hidden from sight and from access without breaking the seal. One of the advantages of this arrangement is that the postage stamp 15 may be utilized as the sealing member when this container

is designed to be transmitted through the mails. Any other equivalent seal may be utilized, however, depending upon the adaptation of the invention. The stamp or seal holds the bent extremity 13' of the locking member in flat position as shown in Fig. 4, but this element may readily be grasped upon breaking the frangible seal. It is also to be understood that the bent extremity 13' may be broken off after the locking member has been inserted into its locking position if so desired, in which event the unlocking of the container is rendered much more difficult and the safety of the contents enhanced.

As hereinbefore premised, the device may be used for the purpose of carrying missives through the mail but we do not wish to be confined to such use as it could readily be employed as a shipping tag holder or in other ways where a durable and strong holding element is desired, for equivalent purposes.

Having thus described the invention, what is claimed is:

1. A container of the class described comprising openable sections, one of said sections having an opening therein, a locking pin inserted through said opening to lock the sections together, the free terminal of said pin lying in said opening below the surface of its section and constituting a fingerpiece, and a frangible seal attached concealing said opening and coöperating with the fingerpiece aforesaid to hold the pin against displacement and inaccessible without fracture of the seal.

2. A container of the class described comprising coöperative sections, locking elements on said sections lying between the sections when the latter are close together, one of said sections having an opening therein, a locking member insertible through the opening into said locking elements for holding the sections together, said locking member having a manipulating projection arranged when the member is in locking position to lie contiguous to the face of one of said sections, and sealing means adapted for attachment to the face of the last mentioned section over the opening and projection whereby to hold the locking member from displacement and completely concealing said opening and projection.

3. A container of the class described comprising openable sections adapted to receive therebetween indicia bearing contents, one of said sections having its material cut out to form sight openings for disclosing the indicia aforesaid, said cut out material being arranged to form locking elements, and means coöperating with said locking elements to hold the sections closed.

4. A container of the class described comprising openable sections adapted to receive

therebetween indicia bearing contents, each of said sections having its material cut out to form openings, said cut out material being rolled back to form coating locking eyes, 5 and a locking member insertible into said eyes when in registering position for holding the sections in closed position.

5. A container of the class described comprising openable sections adapted to receive 10 cards and similar articles therein, one of said sections having its material about the central portion thereof partly cut out so as to leave narrow severable connecting tongues for said central portion whereby the latter 15 may be detached, said container constituting a frame for the contents upon detachment of the central portion aforesaid.

6. As a new article of manufacture, a safety carrier consisting of a sheet of ma-

terial of elongated formation, said material 20 being bent intermediate its length to form front and rear sections adapted to be folded upon each other, the material of the front section being cut out to form sight openings and having internal locking eyes, the rear 25 section having its material partly cut out to form a central separable panel, one of the sections being provided with holding flanges to receive the contents of the holding means, the other of said sections having flanges engageable about its co-operative section, and a locking pin engageable with the locking eyes aforesaid to hold the device in closed position.

In testimony whereof we affix our signatures.

CHARLES W. FISCHER.
RUDOLF SCHAMBER.
